UNITED STATES PATENT OFFICE.

CHARLES L. FARISH, OF LAKELAND, FLORIDA.

GOLF-BAG STAND.

Application filed July 5, 1924. Serial No. 724,240.

This invention relates to improvement in golf bag stands and consists of the matters hereinafter described, and more particularly pointed out in the appended claims. The object of the invention is to provide a device which may be readily attached to the ordinary golf bag and which may be automatically expanded into a set-up or open position by the act of bringing it to rest upon the ground and may be as readily and automatically collapsed or closed so as to be conveniently carried by the action of lifting the stand and the bag to which it is attached.

10 A further object of the invention is to provide a device having but two legs, which when the bag is set at rest upon the ground will open both rearwardly and laterally to provide with the bag a tripod which cannot easily fall over.

15 These objects of the invention, as well as the many advantages thereof, will more fully appear as I proceed with my specification.

In the drawings:

20 Fig. 1 is a view representing a side elevation of a golf bag with my improved stand device applied thereto.

25 Fig. 2 is a view representing a side elevation with the stand as it appears in set-up position supporting a golf bag.

30 Fig. 3 is a view on an enlarged scale showing the stand device in side elevation with the leather covering, which is designed to enclose it, partially removed, and shown in vertical section.

35 Fig. 4 is a view of the parts shown in Fig. 3 looked at from a position at right-angles to the position of observation of Fig. 3.

40 Fig. 5 is a detailed sectional view in a plane indicated by lines 5-5 of Fig. 4.

45 Fig. 6 is a cross-sectional view in a plane indicated by lines 6-6 of Fig. 3.

Referring now in detail to that embodiment of the invention illustrated in the accompanying drawings; 10 indicates a golf bag of the usual kind and 11 indicates my improved stand device, which is capable of ready and easy attachment to said bag so as to provide in connection therewith a tripod-like stand.

50 The golf bag as herein shown is of the kind having a heavy fabric tubular body, which is open at its top end and is reinforced and closed at its bottom end by the familiar leather boot or bottom 10^a. The stand de-

vice includes a sheet metal, arcuate, vertically, elongated shell or band 12 which is adapted to fit and partially surround the bag 10 near its upper end to which it is riveted or otherwise attached, as will be presently described. The shell or band 12 has preferably formed intermediate its top and bottom ends an annular recess 13.

55 14-14 indicate the two folding legs of the stand, said legs forming with the bag itself, the three legs of the tripod. The two legs are pivoted to the shell or band 12 by means of radially extending pins 14^a which are spaced horizontally and arcuately a distance apart less than 180 degrees. The legs as shown consists of round rods or bars 15 which are each fixed in any suitable manner to an arm 16 in such manner as to provide a bell-crank lever fulcrumed on the associated pin 14^a. Each arm 16 is formed to correspond with the annular surface of the recessed part 13 of the shell or band 12.

60 17 indicates a handle or bail for operating the device. Said handle is operatively connected to the shell or band 12 by a slot and pin connection so that it is capable of a limited vertical movement upon said shell or band, the slot acting as a guide to determine the vertical up and down movement of the handle.

65 18, 19 indicate the pin and slot in the bottom end of the handle and 20, 21 indicate the pin and the slot at the upper end of the handle. The proximate ends of the arms 16 are connected together by an arcuate bar 22 and the pin 20 connects the upper end of the handle 17 to the said bar 22. The bar 22 and the arms 16 are connected together in such a manner as to provide for a small amount of lost motion by means of pins and slots indicated at 23.

70 When the handle 17 is in its uppermost position, the legs 14 are closed against the sides of the bag as shown in Fig. 1. When the handle 17 is in its lowermost position, the legs have been swung upon their pivot pins 14^a to bring them into the position shown in Fig. 2. Here, on account of the fact that the pins 14^a are less than 180 degrees apart, the bottom ends of the legs have been widely separated, as will be manifest, thus providing a wide base for the bag.

75 100 As will be readily understood, the movement of the handle described is easily accomplished when the player sets the bag upon the ground. The folding up of the legs will

be accomplished with equal ease by lifting the bag by the handle, which on account of the weight of the bag will cause the handle to rise and thus bring it to its uppermost position with the legs 14 folded against the sides of the bag.

As shown, the shell or band 12 is cut away at the sides towards the bottom end, leaving only a narrow tongue 24 (see Fig. 4) for the attachment of the bottom end of the handle. The shell or band is preferably covered by a shield 25 of a strong flexible material such as leather which may be cut to substantially fit the shell or band with openings formed therein as at 26—26 for the handle to extend through. This shield protects the metal parts from the weather and prevents them from rusting. The leather shield is attached to the bag in any convenient manner, preferably by means of the same rivets that secure the shell or band to the bag. The shield is also made, as shown in the drawings, cylindrical at the top so as to completely surround the bag as shown in Figs. 1 and 2.

While in describing my invention, I have referred to certain details of construction, as well as arrangement of parts, I do not wish to be limited thereto, except as may be pointed out in the appended claims.

I claim as my invention:—

1. A device of the kind described comprising in combination, a rigid shell adapted to embrace and to be secured to a golf bag, means providing a guide extending vertically of said shell, a handle mounted in said guide and capable of a limited vertical movement therein, leg members pivoted to said shell on axes extending substantially radially with respect to the longitudinal axis of said bag, and spaced less than 180 degrees apart on each side of said guide, and means operatively connecting said leg members to said handle.
2. A device of the kind described comprising in combination, a rigid shell adapted to embrace and to be secured to a golf bag, means providing a guide extending vertically of said shell, a handle mounted in said guide and capable of a limited vertical movement therein, bell-crank levers pivoted to said shell on each side of said guide and spaced less than 180 degrees apart, said bell-crank levers each including two arms, a leg fixed to one arm of each bell-crank lever, and means operatively connecting the other arm of each bell-crank lever to said handle.
3. A device of the kind described comprising in combination, a rigid shell adapted to embrace and to be secured to a golf bag, means providing a guide extending vertically of said band, a handle mounted on said guide and capable of a limited vertical movement thereon, bell-crank levers pivoted to said band on each side of said guide and

spaced less than 180 degrees apart, said bell-crank levers each including two arms, legs for the bag, each constituting a prolongation of one arm of a bell-crank lever, and means connecting the other arm of each bell-crank lever to said handle.

4. A golf bag provided with a movable handle, movable supporting legs for the bag, means whereby said legs are controlled by movement of said handle relatively to the bag so that the legs swing outward away from the sides of the bag when the lower end of the bag is placed on the ground and the handle is moved downward, the upper ends of the legs being spaced apart a distance by the upper portion of the bag, the lower ends of the legs being a greater distance apart when in position to support the bag in an inclined position with the handle on the upper side thereof, and the legs being adapted to fold against the opposite sides of the bag when the handle is moved upward by raising the bag from the ground.

5. A golf bag provided with a movable handle, movable supporting legs for the bag, means whereby said legs are controlled by movement of said handle relatively to the bag, so that the legs swing outward away from the sides of the bag when the lower end of the bag is placed on the ground and the handle is moved downward, the upper ends of the legs being spaced apart a distance by the upper portion of the bag, the lower ends of the legs being a greater distance apart when in position to support the bag in an inclined position with the handle on the upper side thereof, and the legs being adapted to fold against the opposite sides of the bag when the handle is moved upward by raising the bag from the ground, said legs being pivoted less than one hundred and eighty degrees apart, near the side of the bag that has the handle, with the axis of the legs radial with the axis of the bag, whereby said legs swing away from each other when they are swung into operative position.

6. A device of the kind described comprising a sheet metal shell adapted to be attached to a golf bag, said shell being provided intermediate its ends with a recessed base, said base presenting an attaching surface, legs pivoted to said attaching surface on axes at right angles thereto, each leg having a bell crank arm, an operating strap, means connecting said arms and strap permitting lost motion, said base and strap being provided with interengaging correlated guiding parts and a handle connected to said strap and adapted for operating same.

In testimony that I claim the foregoing as my invention, I affix my signature this 2nd day of July, A. D. 1924.

CHARLES L. FARISH.
